ADJUSTING DEVICE FOR WIRELESS APPARATUS

Filed May 11, 1922

FIG. 1.

FIG. 2.

INVENTOR:
Harold D. Waterhouse
by Russell F. Hatch, Atty

UNITED STATES PATENT OFFICE.

**HAROLD D. WATERHOUSE, OF WEST HARTFORD, CONNECTICUT, ASSIGNOR TO
WILLIAM A. READY, OF BROOKLINE, MASSACHUSETTS.**

ADJUSTING DEVICE FOR WIRELESS APPARATUS.

Application filed May 11, 1922. Serial No. 560,024.

This invention relates to wireless apparatus, more specifically to adjusting mechanism for positioning the dial or other circular part connected with an adjustable part 5 of such apparatus, such as the variometer, variocoupler or condenser.

Devices of this character are usually provided with a dial connected to the movable part, by which it may be moved for the purpose of tuning to various wave lengths and for other purposes. In order to secure the best results, particularly for telephoning, it is necessary that a very delicate setting of the dial shall be possible. If the dial turns 10 a little hard there is a strong tendency for it to jump when an attempt is made to move it through a slight angle and if it moves easily so as to overcome the jumping, the dial and connected parts are likely to turn 15 enough to destroy the accuracy of the setting, due to vibration or jarring of the apparatus.

One object of the present invention is to provide a device for setting the dial of a 20 wireless apparatus, by which it may be moved through minute angles with accuracy and without jumping or over-running.

Another object is to provide such an adjusting device which will hold the parts in 25 adjusted position without danger of accidental displacement.

The various features of the invention employed to the accomplishment of these objects, and such others as may hereinafter appear, will best be understood from the following description together with the accompanying drawings in which:

Figure 1 is a front elevation of a piece of 30 wireless apparatus showing a dial and the adjusting means therefor; and

Figure 2 is a section on an enlarged scale, taken on the line 2-2 of Fig. 1.

A dial 5 shown in Fig. 1 is connected through suitable mechanism, with the part 45 of the apparatus to be adjusted so as to turn it about an axis or to slide it with relation to its co-operating part. The dial is usually

provided with a knob 6 by which it may be turned. It is difficult, however, to turn the dial accurately through small angles, such as 50 a part of a unit indicated by graduations 7 with reference to a fixed pointer 8.

This invention contemplates the provision of an actuator for the dial 5, capable of being moved into inoperative position to permit rapid but rough adjustment of the dial by the knob 6. In order to permit the device to be readily attached to apparatus in common use, it is preferably arranged for frictional engagement with the periphery of the 60 dial. A yielding surface is provided to engage the edge of the dial which surface, as illustrated, is formed by a comparatively soft rubber band 10 carried by an annulus 13. A knob 11 is operatively connected with the annulus and adapted to be rotated about a stud formed by a screw 12. This knob may be directly connected with the band and the reducing ratio of the diameter of the band and the dial may be utilized to produce a delicate adjustment of the dial. It is preferred, however, to introduce a speed reducing mechanism between the knob and the dial engaging member. The speed reducing mechanism is illustrated as a differential gear mechanism comprising a fixed internal gear 14 and a rotatable gear 15 formed in the annulus 13, of substantially the same pitch diameter as the gear 14 but having one tooth more or less than that gear. 70 Both of these gears are in mesh with a pinion 16 freely rotatable on a stud 17 mounted eccentrically on the knob 11. By this construction, one revolution of the knob 11 causes the movable gear to be advanced an 75 amount equal to one tooth, thereby turning the dial a corresponding amount. It is preferred that this amount shall be equal to one unit of the graduations on the dial.

In order that the device may be moved into and out of operative relation to the dial 5, it is carried by an arm 19 pivotally mounted on a screw 20 fixed on the front of the box 21. The free end of the arm is

turned up at 22 to provide a handle and a spring 23 is arranged to hold the arm yielding toward the dial as shown in Fig. 1, or, in the other position of the arm, to hold it in inoperative position with respect to the dial. The arm may also be provided with frictional means for holding it in position, such as the screw 24 which holds a spring washer 25 against the arm.

10 In the embodiment of the invention selected for the purpose of illustration, the screw 12 forming a pivot for the adjusting knob 11, is mounted in a cup 26 fixed in a recess in the arm 19. The fixed gear 14 is 15 formed in a boss pressed up from the arm 19, the outside of which forms a bearing for the annulus 13.

10 The operation of the device is apparent from the foregoing description and it is also 20 obvious that it can be readily attached to the various wireless instruments now in common use.

15 It is to be understood that the particular embodiment of the invention illustrated and 25 described, is but one example of several modifications which may be employed, and which fall within the scope of the appended claims.

What is claimed as new, is:—

30 1. An adjusting device for wireless apparatus, including a dial, a roll movable into and out of operative relation to the dial, a knob for turning the roll, and a differential gear connection between the knob and the roll.

2. An adjusting device for wireless apparatus, including a dial, an arm mounted to swing toward and from the dial, a roll mounted on the arm and adapted to engage the dial, a differential gear mechanism for turning the roll, and means for holding the arm in position toward or from the dial.

3. An adjusting device for wireless apparatus, including a dial, an arm mounted to swing toward and from the dial, an internal gear formed in the arm, an annulus having an internal gear of a different number of teeth concentric with the first gear, a yielding dial engaging surface on the annulus, a knob carry a gear in mesh with the internal gears, and means for holding the arm toward the dial.

4. A freely rotatable dial, a pivotally mounted arm, a roller journaled upon the 55 arm for rotation about an axis parallel with the axis of the dial and movable into and out of contact with the periphery of the dial when the arm is moved about its pivot, and a handle connected with the roller for rotating the latter with respect to the arm to rotate the dial.

5. A freely rotatable dial, a pivotally mounted arm, a roller journaled upon the arm and movable into and out of contact 60 with the periphery of the dial when the arm

is moved about its pivot, a handle connected with the roller for rotating the latter with respect to the arm to rotate the dial, and a stop for limiting the movement of the arm in one direction about its pivot. 70

6. A freely rotatable dial, a pivotally mounted arm, a roller journaled upon the arm, for rotation on an axis parallel with the axis of the dial and movable into and out of contact with the periphery of the dial when the arm is moved about its pivot, a handle connected with the roller for rotating the latter with respect to the arm to rotate the dial, and a handle connected with the arm for moving the latter about its 75 pivot. 80

7. A freely rotatable dial, a pivotally mounted arm, a roller connected with the arm for rotation on an axis substantially parallel with the axis of the dial and movable into and out of contact with the periphery of the dial when the arm is moved about its pivot, a handle connected with the roller for rotating the latter with respect to the arm to rotate the dial, and a spring 85 for assisting the movement of the arm about its pivot. 90

8. A freely rotatable dial, a lever, a roller supported by the lever for rotation about an axis substantially parallel with the axis 95 of the dial, said roller movable into and out of engagement with the dial as the lever is moved about its pivot, and a knob like device connected with the roller for rotating the latter with respect to the lever to 100 rotate the dial.

9. A freely rotatable dial, a pivotally mounted lever, a roller mounted upon the lever for free rotation with respect thereto and on an axis substantially parallel with the axis of the dial, said roller being adapted to engage the periphery of the dial when the lever is moved in one direction about its pivot, and a knob like device connected with the axis of the roller for rotating the latter to 105 rotate the dial. 110

10. A freely rotatable dial, a pivotally mounted lever, a roller mounted upon the lever for free rotation with respect thereto on an axis substantially parallel with the axis of the dial, said roller being adapted to engage the periphery of the dial when the lever is moved in one direction about its pivot, a knob like device connected with the axis of the roller for rotating the latter to 115 rotate the dial, and a spring for holding the roller against the periphery of the dial. 120

11. A freely rotatable dial, a pivotally mounted lever, a roller mounted upon the lever for free rotation with respect thereto, said roller being adapted to engage the periphery of the dial when the lever is moved in one direction about its pivot, a knob like device connected with the axis of the roller for rotating the latter to 125 rotate the dial, and 130

a spring for maintaining the lever in either of the positions to which it has been adjusted about its pivot.

12. A freely rotatable dial, a freely shift-
able support, a roller mounted upon the
support for rotation about an axis substan-
tially parallel with the axis of the dial, said
roller being movable into and out of en-
gagement with the dial as the said support

is moved toward and away from the dial, re-
silient means for maintaining the support
in each of its adjusted positions and a knob
like device connected with the roller for
rotating the latter with respect to the said
support to rotate the dial. 10
